UNITED STATES PATENT OFFICE.

RALPH F. FRAZIER, OF BALTIMORE, MARYLAND.

BELL-CRANK LEVER AND SUPPORT FOR USE WITH WIGGLERS.

1,306,424.

Specification of Letters Patent. Patented June 10, 1919.

Application filed December 30, 1918. Serial No. 268,987.

To all whom it may concern:

Be it known that I, RALPH F. FRAZIER, a citizen of the United States, residing at Baltimore, in the State of Maryland, have in-

5 invented certain new and useful Improvements in Bell-Crank Levers and Supports for Use with Wigglers; and I do hereby declare the following to be a full, clear, and exact description of the invention, such as will enable others skilled in the art to which it ap-

10 pertains to make and use the same.

My invention relates to bell crank levers and supports for use with wigglers.

One object of my invention is to provide a 15 simple, cheap and effective bell crank lever for use with wigglers which can form an article of commerce and be sold for use with existing wigglers or can be furnished as an appurtenance with new wigglers.

20 Another object of my invention is to provide a bell crank lever and support therefor for use with wigglers which shall have a limited amplitude of swing so that it may be readily applied to the wiggler.

25 A further object of my invention is to provide a bell crank lever and support for use with wigglers, the support being so arranged that it may be readily adapted for use with many types of wigglers.

30 In carrying out my invention, I make use of the instrumentalities illustrated in the accompanying drawings in which:—

Figure 1 is a plan view of a wiggler with my improved bell crank lever and support 35 secured thereon.

Fig. 2 is an enlarged view of the bell crank lever and support shown in Fig. 1 looking in the direction of the arrow 2 in said figure.

40 Fig. 3 is a section along the line 3—3 in Fig. 1 looking in the direction of the arrows.

Fig. 4 is a view of the parts shown in Fig. 2 looking in the direction of the arrow 4 in said figure.

45 In the drawings:—

10 represents a wiggler having a dial 11 over which the pointer 12 is moved by suitable mechanism, the latter being actuated by the operating pin 13 which is the terminus 50 of a rod that slides through the sleeve 14.

The sleeve 14 terminates in the taper 15 which fits snugly within the taper hole 18 in the interior of the bushing 17. The bushing 17 is preferably tapered upon the outer 55 side and fits snugly within a taper hole 18 formed in the support 19. The collar por-

tion 20 of the support 19 surrounding the taper hole 18 may be tapered in shape, as shown in the drawings, or may be of any approved shape.

60 Formed integrally with the collar portion 20 are ears 21—21 between which is the slot 22 which extends to the taper hole 18. A pintle 23 is secured in a suitable hole provided near the ends of the ears 21—21, and 65 in the slot 22 and there is revolvably mounted upon the pintle 23 the bell crank lever 24.

The bell crank lever 24 is provided with a rounded nose 25 for application to the work, 70 said nose being formed at the outer extremity of the arm 26. The lever 24 is also provided with a finger 27 which is shaped and located to contact with the operating pin 13, as shown in Fig. 1. The lever 24 is also provided with a stopping arm 28 which is shaped 75 and located to strike the bushing 17.

The manner of use and operation of my improved bell-crank lever and support is as follows:—

80 The taper hole 16 is to be placed over the taper 15 of the sleeve 14 and pressed in in order to secure the support 19 upon the sleeve 14. By means of any suitable clamping arrangement, the wiggler 10 is secured upon the tool with which it is to be used and 85 the nose 25 brought into contact with the work which is to be trued. The work being then moved, it is evident that inequalities in the location of the outer surface of said work will cause the nose 25 to vibrate, it being understood that the operating pin 13 is 90 normally pressed toward the left, (see Fig. 1), by a spring forming part of the wiggler, which is no part of my present invention. The inequalities in the location of the exterior surface of the work will be indicated 95 by the position to which the pointer 12 is moved and the work can be shifted until the inequalities are entirely removed or reduced to any satisfactory degree.

100 It is obvious that during certain operations considerable stress may come upon the nose 25 in the direction of the arrows pointing toward the dotted line 3—3 in Fig. 2 or in the opposite direction, and that said stress 105 will tend to move said nose either upwardly or downwardly (as shown in Fig. 2). For the purpose of resisting these stresses, the arm 28 is arranged for a sliding fit within the slot 22.

110 Referring to Fig. 3, it is evident that if the lever 24 revolves in a clock-wise direc-

tion, its motion will be limited in extent by the contact of the operating finger 27 with the left-hand end of the bushing 17 and that if said lever moves in a counter clock-wise direction, its motion will be limited by contact of the arm 28 with the outer surface of the bushing 17; consequently, the motion of said lever is limited in both directions and when removed from the wiggler 10, said lever is always ready for immediate application to said wiggler without any preceding adjustment of said lever.

It is also evident that I may provide bushings such as 17 having an exterior shaped to fit the taper hole 18 in the body 20 and having interior taper holes 16 of various sizes to suit the tapers 15 on a large number of wigglers; consequently, my improved bell crank lever is suitable for use with wigglers of many kinds.

I claim:

1. In a bell crank lever and support for

use with a wiggler, the combination with a support provided with a hole, ears formed integrally with said support and a pintle 25 supported by said ears, of a bushing mounted in said hole and a lever revolvably mounted on said pin between said ears and provided with a stopping arm located to strike said bushing and limit the movement of said lever.

2. In a bell crank lever and support for use with a wiggler, the combination with a support provided with a hole, ears formed integrally with said support and a pintle 35 supported by said ears, of a bushing mounted in said hole and a lever revolvably mounted on said pin between said ears, said lever comprising a nose for application to work, an operating finger located to strike the end 40 of said bushing, and a stopping arm located to strike the side of said bushing.

In testimony whereof I affix my signature.

RALPH F. FRAZIER.
